ABSTRACT: The disclosure is of a display system including a matrix of gas cells which can be ignited in different combinations to represent characters. In order to balance the change in impedance for the driving circuit represented by the different numbers of gas cells ignited at different times, a second similar matrix of gas cells is provided coupled to the driving circuit and operated as the negative of the first matrix; that is, when selected cells of the first matrix are ignited, the corresponding cells in the second matrix are held off and all others are ignited.

IMPEDANCE BALANCE SYSTEM FOR GASEOUS DISCHARGE DISPLAY PANEL

CROSS-REFERENCE TO RELATED APPLICATIONS

This is a streamline continuation of application Ser. No. 863,392, filed May 14, 1969, and now abandoned, which is, in turn, a continuation of application Ser. No. 669,358 filed Sept. 15, 1967, and now abandoned.

BACKGROUND OF THE INVENTION

This invention relates to the art of display devices and, particularly, to display devices of the type in which a plurality of individual display cells are energized in different combinations to represent different characters. Systems of this type represent variable impedance for the driving circuit each time the combination of display cells is changed.

SUMMARY OF THE INVENTION

Briefly, the invention comprises a system which includes information drive circuitry coupled to a first display device comprising a plurality of individually energizable cells and a second mirror image display device comprising the same number of cells. The impedance seen by the drive circuitry is balanced by reversing the coupling of the two display devices so that, when a cell in the first is ignited, its counterpart in the second is not ignited, and vice versa.

DESCRIPTION OF THE DRAWING

In the drawing:

FIG. 1 is a schematic representation of a system for operating a display device comprising a matrix of gas-filled cells; and

FIG. 2 is a sectional elevational view of a portion of a display device shown in FIG. 1.

DESCRIPTION OF THE PREFERRED EMBODIMENTS

The system of the invention 10 includes a first display panel 20 which comprises a matrix of gas-filled cells 30, each of which can be made to glow when a suitable voltage is applied across the cell. In a typical system, a selected group of cells can be ignited to represent in toto a character such as a number, letter, symbol, or the like.

Essentially, a cell 30 (FIG. 2) comprises an insulating cylinder 40 of glass or the like including an ionizable noble gas such as neon, argon, etc., or mixtures of these gases with or without other gases. A mixture of about 94 percent neon and about 6 percent nitrogen at a pressure of a few hundred mm. Hg is particularly suitable. The gas may be introduced into the cell in any suitable fashion, for example, through a hole in one of the end walls which is sealed after the gas has been introduced.

The cell 30 with this gas filling has "memory"; that is, glow once produced by a firing signal can be sustained after the energizing signal is removed by the application of a smaller sustaining signal. This phenomenon appears to be due to charges stored on the wall of the envelope in the gas. Cell 30 has transparent glass top and bottom walls 50 and 60 which carry transparent electrodes 70 and 80 of gold or the like. Thus, the matrix of cells which make up display panel 20 may comprise separate and distinct cells of this type, or it may be made of a sandwich of glass plates including a central apertured plate whose apertures form the cells and top and bottom plates. This construction need not be shown in detail.

Generally, the cells 30 in display device 20 are arranged in rows and columns, and they may be provided in any number, depending on the required function. For convenience of illustration, three rows and three columns of cells are shown in the drawing. The display device or panel 20 includes a common electrode 70 which is called a row electrode for each row of cells 30, and a common electrode 80 known as a column electrode for each column of cells. The row electrodes 70 are all formed on one surface of the panel, and the column electrodes 80 are formed on the opposite surface.

The display system of the invention includes a second display panel 20' identical to the first and containing the same number of gas display cells 30'. Structural elements in the second panel carry the same reference numerals as the corresponding elements in the first panel but with a prime designation.

In operation of a display panel 20 of the type shown, signals are applied to the row and column electrodes or conductors 70 and 80, and, generally, one or more cells have the proper energizing potential applied across them, and these cells glow and provide the desired character representation. This type of operation of display panels is generally well known.

The system of the invention includes a driver circuit 100 for the row conductors 70 and a driver circuit 110 for the column conductors. Circuits of this type are generally well known and include decoders, amplifiers, and the like for receiving information in some coded form and converting it to signals which energize the proper row and column conductors. A source 112 of alternating potential which serves as a sustaining signal is also connected across all of the cells 30 of panel 20.

According to the invention, at some convenient point in the circuit, the information signals to be applied to the row conductors 70 are coupled through suitable inverter circuits 120 to the row conductors 70' of the second display panel 20'. Similarly, the information signals to be coupled to the column conductors of the first panel 20 are connected through suitable inverter circuits 120' to the column conductors of the second panel 20'. The sustaining signal source 112 is also connected across all cells in panel 20'.

In operation of the system, driver circuits 100 and 110 produce outputs which provide energizing potentials across selected cells in the first display panel 20. These cells are caused to glow and represent information which can be sustained. Similarly, the reverse potentials are applied across the corresponding cells of the second panel 20' so that cells which glow in the first panel do not glow in the second panel, and vice versa. This arrangement provides a constant impedance balance for the driver circuits 100 and 110.

What is claimed is:

1. A display system comprising
a first panel including a plurality of gas-filled cells which are adapted to glow individually and are arrayed in rows and columns in a matrix,
first electrode connections to each cell of said first panel for applying firing potential thereto,
a second panel including a plurality of gas-filled cells which are adapted to glow individually and are arrayed in rows and columns in a matrix,
second electrode connections to each cell of said second panel for applying firing potential thereto,
first circuit means coupling input information signals to said first electrode connections, and
second circuit means coupling the inverse of said information signals to said second electrode connections to said second panel whereby selected cells in said first panel are caused to glow while the corresponding cells in said second panel do not glow, and
third circuit means including a source of sustaining signals coupled to both of said panels.
2. A display system comprising
a first panel including a plurality of gas-filled cells which are adapted to glow individually and are arrayed in rows and columns,
a separate first row electrode coupled to each row of cells of said first panel for applying information signals thereto,
a separate first column electrode coupled to each column of cells of said first panel for applying information signals thereto,
a second panel including a plurality of gas-filled cells which are adapted to glow individually and are arrayed in rows and columns,
a separate second row electrode coupled to each row of cells of said second panel for applying information signals thereto,

a separate second column electrode coupled to each column of cells of said second panel for applying information signals thereto,
 first circuit means coupling input information signals to said first row and column electrodes, and
 second circuit means coupling the inverse of said information signals to said second row and column electrodes to said second panel whereby selected cells in said first panel are caused to glow while the corresponding cells in said second panel do not glow, and
 third circuit means including a source of sustaining signals coupled to the row and column electrodes of said first and second panels.

3. A display system comprising
 a first panel having top and bottom surfaces and including a plurality of cells filled with an ionizable gas which are adapted to glow individually and are arrayed in rows and columns,
 a separate first row electrode on said top surface of said panel and coupled to each row of cells of said first panel for applying information signals thereto,
 a separate first column electrode on said bottom surface of said panel and coupled to each column of cells of said first panel for applying information signals thereto,
 a second panel having top and bottom surfaces and including a plurality of cells filled with an ionizable gas which are adapted to glow individually and are arrayed in rows and columns,
 a separate second row electrode connected to each row of cells of said second panel for applying information signals thereto,
 a separate second column electrode connected to each column of cells of said second panel for applying information signals thereto,
 a first drive circuit coupled to said first row electrodes and through an inverter circuit to said second row electrodes, and
 a second drive circuit coupled to said first column electrodes and through an inverter circuit to said second column electrodes whereby selected cells in said first panel are caused to glow while the corresponding cells in

said second panel do not glow, and
 third circuit means including a source of sustaining signals coupled to the row and column electrodes of said first and second panels.

5. 4. The system defined in claim 1 wherein the gas in said cells comprises a mixture of neon and nitrogen.
 5. The system defined in claim 1 wherein the gas in said cells is a mixture of about 94 percent neon and about 6 percent nitrogen.

10. 6. The system defined in claim 1 wherein the gas in said cells is a mixture of about 94 percent neon and about 6 percent nitrogen at a pressure of a few hundred mm. Hg.
 7. The system defined in claim 1 wherein the first and second panels have the same number of cells.

15. 8. The system defined in claim 1 wherein the first and second panels are substantially identical.
 9. The system defined in claim 7 wherein the impedance characteristics of the corresponding cells of the two panels are substantially the same.

20. 10. The system defined in claim 9 further including third circuit means coupled to the cells of said first and second panels, said third circuit means being characterized by a constant impedance characteristic substantially equal to that of one entire panel.

25. 11. The system defined in claim 7 further including third circuit means connected to the cells of said first and second panels to supply sustaining signals to said cells, said third circuit means providing a constant impedance characteristic for the sustaining signals.

30. 12. The system defined in claim 11 wherein said third circuit means is characterized by a constant impedance characteristic substantially equal to that of one entire panel.
 13. The system defined in claim 1 wherein the first circuit means couples input information signals to n gas-filled cells in said first panel, n being any integer, and the second circuit means simultaneously couples input information signals to $N-n$ gas-filled cells in said second panel, N signifying a predetermined integer equal to or greater than n , further including third circuit means coupled to N cells of said first and second panels, said third circuit means always reflecting the impedance characteristic of N gas-filled cells.
